No. 826,211.

PATENTED JULY 17, 1906.

M. L. YOUNG.

HOVER.

APPLICATION FILED APR. 21, 1906.

UNITED STATES PATENT OFFICE.

MARY L. YOUNG, OF SHERMAN, NEW YORK.

HOVER.

No. 826,211.

Specification of Letters Patent.

Patented July 17, 1906.

Application filed April 21, 1906. Serial No. 313,049.

To all whom it may concern:

Be it known that I, MARY L. YOUNG, a citizen of the United States, residing at Sherman, in the county of Chautauqua and State of New York, have invented certain new and useful Improvements in Hovers, of which the following is a specification.

This invention relates to new and useful improvements in hovers.

10 The invention pertains particularly to that type in which the hover is suitably supported and is adjustably mounted upon its support.

The invention aims as a primary object to eliminate the disadvantages of the stationary 15 hovers ordinarily employed, such as piling and smothering of the chicks and the diseases consequent therefrom.

To this end the invention comprises a hover which may be adjusted to vary the distance 20 between the floor and the ceiling and to thus compensate for the growth of the fowls.

The detailed construction will appear in the course of the following description, references being had to the accompanying drawings, forming a part of this specification, like 25 numerals designating like parts throughout the several views, wherein—

Figure 1 is a longitudinal section of the hover. Fig. 2 is a top plan view thereof. 30 Fig. 3 is a detailed longitudinal section of the adjusting device, and Fig. 4 is a detailed longitudinal section of the frame of the hover.

In the practical embodiment of my invention I employ a base 1, designed to rest upon 35 suitable support and provided centrally thereof with a plate 2, formed with a central collar 3, within which is rigidly held a vertical post 4, that serves as a supporting element for the hover proper. This mode of securing 40 the post 4 to the base 1 is purely arbitrary, and any other suitable devices may be employed for the same purpose.

The hover comprises a spider-frame 5 of 45 cruciform shape, provided at the junction of its arms with opening 6, loosely surrounding the post 4. Rigidly secured to the ends of the cross-arms of the frame 5 is an outer annulus 7, which has connection with an inner annulus 8, concentric therewith and spaced away 50 therefrom. The sides and top wall of the hover are constituted of an integral section of textile or other flexible material 9, formed with a central aperture through which the post 4 passes.

55 The section 9 has its edge passed through the space between the annuli 7 and 8, as at

10, and is securely and tautly held by the connections of said annuli, such as screws 11. The portions of material which hang from the annuli are provided with longitudinal slits 12, 60 arranged at regular angles, whereby a circular series of depending curtains 13 are provided, which constitute the side walls of the hover.

The hover thus constructed is suspended 65 from the post 4 by virtue of its connection with a sleeve 14, formed with an annular outstanding flange 15 and carrying an adjusting set-screw 16, which frictionally engages the post 4. The hover is positively supported 70 from the sleeve 14 by diagonal guy-wires 17, extending radially from said sleeve. The wires 17 are secured to the sleeve and the annulus 7 by any suitable connections, of which an operative form is disclosed in Figs. 3 and 75 4. The upper end of each wire 17 is passed through an aperture in the flange 15, and then said end is bent upon itself to form a closed loop, as shown at 18. The free end of each guy 17 is passed through an aperture 80 therefor in the annulus 7 and is bent into the form of a hook, as at 19.

It is to be understood that the free ends of the guy-wires 17 may be secured to the sleeve 14 and annulus 7 in any manner desired, the 85 showing of the drawings being a purely arbitrary disclosure.

Having fully described my invention, I claim—

1. A hover comprising a supporting-base, 90 a vertical post, an open frame slidable upon said post, a section of textile fabric carried by said frame, a collar slidably mounted upon said post, means for retaining said collar in any position to which it is moved and guy-wires extending radially from said collar and connecting the same with said frame.

2. A hover comprising a supporting-base, a vertical post, an open frame slidable upon said post, a pair of annuli arranged in concentric relation and carried by said frame, a section of textile fabric carried by said frame and clamped between said annuli, a collar slidably mounted upon post, means for locking said collar at any selected position upon 105 said post and guy-wires extending radially from said collar and having connection with said annuli.

3. A hover comprising a supporting-base, a vertical post, an open frame slidable upon said post, a pair of annuli arranged in concentric relation and carried by said frame, a sec-

tion of textile fabric carried by said frame and clamped between said annuli, a collar slidably mounted upon said post, means for locking said collar at any selected position upon said post and elements connecting said collar to said frame whereby the latter is positively suspended from the former.

In testimony whereof I affix my signature in presence of two witnesses.

MARY L. YOUNG.
